PRESSURE RELIEF VALVE

Jonathan A. Willetts, Rte. 3, P.O. Box 340-A,
Annapolis, Md. 21403

Filed Feb. 2, 1971, Ser. No. 112,104

Term of patent 14 years

Int. Cl. D23—01

U.S. Cl. D23—19

Fig. 1

Fig. 2

Fig. 3

Fig. 4

Fig. 5

FIG. 1 is a front elevational view of a pressure relief valve, showing my new design;

FIG. 2 is a top plan view thereof;

FIG. 3 is a bottom plan view thereof;

FIG. 4 is a side elevational view thereof, the opposite side being a mirror image of the side shown; and

FIG. 5 is an enlarged perspective view thereof with portions omitted for convenience of illustration.

I claim:

The ornamental design for a pressure relief valve, as shown and described.
